UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING COMPANY, A CORPORATION OF PENNSYLVANIA.

BLADE-MOUNTING.

1,375,111.

Specification of Letters Patent. Patented Apr. 19, 1921.

Application filed March 31, 1917. Serial No. 158,978.

To all whom it may concern:

Be it known that I, HENRY F. SCHMIDT, a citizen of the United States, and a resident of Pittsburgh, in the county of Allegheny and State of Pennsylvania, have made a new and useful Invention in Blade-Mounting, of which the following is a specification.

This invention relates to blade mountings and has for an object to produce a blade 10 mounting which will prevent bending stresses due to eccentric loading of the members of the mounting.

A further object is to produce a blade mounting which is simpler, lighter, more 15 compact, and cheaper than other blade mountings now in use and known to me.

A further object is to produce a blade mounting which allows the weight of all the parts of a rotor wheel to be reduced.

20 A further object is to produce a blade mounting which is so constructed that wide flanges on the blade shank or blade carrying element are unnecessary.

These and other objects are attained by 25 means of the blade mounting herein described, and illustrated in the drawings accompanying and forming a part hereof.

In the drawings: Figure 1 is a sectional view of an embodiment of my invention.

30 Fig. 2 is a sectional view of another embodiment of my invention.

Fig. 3 is a sectional view of a blade mounting in which a somewhat different device is employed in accomplishing my invention.

35 One of the simplest forms of blade mounting is the familiar T-slot construction. A slot is cut in either the blade carrying element or the shank of the blade, and the other member is provided with a T-shaped tongue

40 which fits snugly in the T-slot. A common construction is that in which the tongue is formed on the blade, or blade shank, and the T-slot in the blade carrying element, as this member may be conveniently broadened or

45 flanged so as to furnish material to allow the slot to be formed without seriously weakening the structure. The pull of the blade due to the force of the steam acting on it, or to centrifugal force, or to a combination of

50 both, tends to spread the groove and allow the T-shaped tongue to slip out. This tendency is ordinarily resisted by the extra amount of metal allowed around the groove.

It is understood that the tongue is symmetrically loaded and is therefore only subjected

to pure tension stresses, while the material in which the groove is formed is eccentrically loaded and is subjected to heavy bending stresses.

My invention consists in providing means 60 for counteracting the tendency of the groove to open out, or spread, due to eccentric loading, and to therefore eliminate substantially all bending strains. The resulting joint is as strong or stronger than joints built after 65 the old construction, and is considerably lighter and more compact. These features are of especial value where weight and space are both of unusual importance. The novel construction whereby I prevent bending 70 strains due to eccentric loading is quite simple and is as easy to form as the old construction, hence my invention has the advantages of reduced weight and space as well as the simplicity, strength and cheapness of the old construction.

One of the greatest advantages of my invention is that the elimination of the heavy blade mounting rim makes possible a much lighter rotor wheel throughout. Such a rim, 80 at the high speeds commonly employed, is not capable of fully resisting the stresses due to centrifugal force without the reinforcing and supporting effect of the body and hub of the rotor wheel. Consequently 85 the entire wheel must be made heavy to properly resist the stresses occasioned by the heavy rim. By means of my invention the heavy rim is eliminated and consequently the weight of the rest of the wheel may be 90 reduced. If desirable the hub portion may be dispensed with in built up rotors as it is no longer needed as a reinforcing element of the wheel.

In Fig. 1 I have illustrated a blade 16 95 mounted on a blade carrying member 17 by means of a T-shaped tongue 18, which fits in a similarly shaped slot in the blade carrying member 17. Owing to its shape, the T-shaped tongue 18 is symmetrically loaded, 100 while the blade carrying element 17 is eccentrically loaded on each side of the groove. Consequently any pull on the tongue 18 exerts a bending stress upon the blade carrying element 17 on each side of the groove and 105 tends to spread apart the material in which the groove is cut. In order to counteract the tendency of the blade carrying element 17 to spread, I employ two sets of compound wedges 19 and 20 for transmitting any 110

stresses due to eccentric loading of the blade carrying element 17 to the shank of the blade 16. As the wedges 19 and 20 are inserted at an angle they effectually clamp together the outer ends of the blade carrying element 17.

In Fig. 2, I have shown a construction similar to that shown in Fig. 1, except that the tongue and groove joint is reversed. A tongue 21 is carried by a blade carrying element 22 and compound wedges 23 and 24 are adapted to reinforce the shank of a blade 25, as before.

In Fig. 3, I have shown a blade mounting, which is a modification of that shown in Fig. 2. As before, a T-shaped tongue 26 carried by a blade carrying element 27 is adapted to hold in place a blade 28, and compound wedges 29 and 30, inserted between the blade carrying element 27 and the shank of the blade 28, are adapted to laterally tie the shank of the blade 28 together.

The advantages gained in weight and space saved through my invention are obvious from the constructions illustrated rendering the invention of particular importance to marine work or in other work where space and weight are of special importance. Furthermore, these advantages are gained with substantially no increase in first cost, with no sacrifice of strength, and with practically the same simplicity of construction.

While I have illustrated and described several modifications of my invention, it will be apparent to those skilled in the art, that various changes, modifications, additions and omissions may be made in the apparatus illustrated without departing from the spirit and scope of the invention, as set forth by the appended claims.

What I claim is:

1. In combination, a blade element, a blade mounting element, a T-shaped tongue formed on one of said elements, an undercut groove formed in the other element and adapted to engage the tongue, wedge bearing surfaces on the tongue bearing element extending on each side from and obliquely to the shank of the tongue, opposed wedge bearing surfaces on said grooved element extending from each side of and obliquely to the groove, said wedge bearing surfaces lying in planes diverging toward the center of said elements and wedges disposed between said bearing surfaces adapted to hold said elements against relative lateral displacement.

2. In combination, a blade element, a blade mounting element, an undercut groove formed in one of said elements, a tongue formed on the other element adapted to engage said groove, wedge bearing surfaces formed on the tongue carrying element on opposite sides of the tongue, opposed wedge bearing surfaces formed on the grooved ele-

ment and extending from each side and obliquely to the engaging surfaces of the groove, and wedges disposed between said bearing surfaces to hold the sides of the grooved element against lateral displacement.

3. The combination with a blade mounting member and a blade member having tongue and groove engagement, the grooved member having a shoulder, and the tongue carrying member being provided with an opposed shoulder spaced from the shoulder of the grooved member so as to form an undercut channel between the shoulders obliquely disposed with respect to the engaging surfaces of the tongue and tongue groove, of a wedge disposed between said shoulders and adapted to hold the members against relative lateral displacement.

4. In combination with a blade element, a blade mounting element, a tongue on one of said elements, a groove in the other element and adapted to engage said tongue, a shoulder formed on the grooved element spaced from the tongue carrying element so as to form a channel between the said shoulder and said tongue carrying element, the inner portion of the channel being of greater width than the outer portion thereof and a wedge disposed in the said groove adapted to hold the said elements against relative lateral displacement.

5. In combination with a blade element, a blade mounting element, a tongue on one of said elements, a groove in the other element adapted to engage said tongue, opposed wedge seats formed on the said elements and extending in planes oblique to the engaging surfaces of the tongue and tongue groove, and wedges bearing between said inclined wedge seats adapted to hold said elements against relative lateral displacement.

6. In combination, a blade element, a blade mounting element, an undercut groove formed in one of said elements, a tongue formed on the other element adapted to engage said groove, inclined wedge seats formed on opposite sides of each of said elements and co-operating to form between the said inclined wedge seats channels of greater width at their inner portions than at their outer portions, said wedge seats extending in planes oblique to the engaging surfaces of the tongue and tongue groove, and wedges bearing against the inclined wedge seats and adapted to hold the said elements against relative lateral displacement.

7. In combination with a rotary blade mounting element and a blade element having tongue and groove engagement, wedge seats formed on the opposed ends of the elements extending in planes inclined outwardly from the plane of rotation lying cen-

trally of these elements, the wedge seats co-operating to form channels of greater width at their inner portions than at their outer portions, wedges disposed in the channels 5 adapted to hold the said elements against relative lateral displacement and adapted to be tightened by the rotational movement of the elements.

8. In combination, a blade element, a 10 blade mounting element, the end of one of the elements being formed with a centrally protruding T-shaped tongue and having wedge bearing surfaces extending outwardly from and forming an angle with the shank 15 of the tongue, the end of the other element being formed with a coöperating T-shaped groove engaging the tongue and having wedge bearing surfaces extending outwardly

from and forming an angle with the longitudinally extending engaging surfaces of 20 the groove, said wedge bearing surfaces co-operating to form between them channels of greater width at the inner than at the outer portions thereof, and wedges disposed in said channels to hold the members against 25 relative lateral displacement and adapted to be tightened by the centrifugal force occasioned by rotary motion of the elements.

In testimony whereof, I have hereunto subscribed my name this 30th day of March, 30 1917.

HENRY F. SCHMIDT.
